ADVERTISING DEVICE

Edward H. Philippi, Evanston, Ill.

Application September 16, 1933, Serial No. 689,778

15 Claims. (Cl. 40—53)

This invention relates to improvements in advertising devices and it consists of the matters hereinafter described and more particularly pointed out in the appended claims.

5 One of the objects of the invention is to provide a device of this kind which at predetermined intervals operates to issue successive coupons or strip portions having suitable indicia thereon and which device includes a mechanism for controlling the periods of such issuance.

10 Another object of the invention is to provide a device of this kind which is electrically operated and controlled and which is of simple construction so that it may be made and assembled at a low 15 cost and which is proof against fraud.

15 A further object of the invention is to provide a device of this kind which is clock controlled and includes means for stopping the clock when the strip is exhausted and which device further includes means operating in timed relation with the 20 periods of issuance of a portion of the strip, for opening and closing the slot out through which said strip portion is issued.

25 Still a further object of the invention is to provide a device of this kind which includes an electric motor for feeding the strip to issue a portion thereof and an electric clock for controlling the operation of the motor so that the device is indeed quiet and at the same time is positive and 30 accurate in its operation.

35 The above mentioned objects of the invention, as well as others, together with the many advantages thereof, will more fully appear as I proceed with my specification.

35 In the drawings:

Fig. 1 is a view in front elevation of the device embodying the preferred form of the invention.

40 Fig. 2 is a view in rear elevation, with the rear cover plate of the casing removed to better show the mechanism within the casing.

45 Fig. 3 is a longitudinal vertical sectional view through the casing of the device, with the mechanism within the same shown in side elevation.

Fig. 4 is a detail vertical sectional view through 45 a part of the feed roll mechanism of the device as taken on the line 4—4 of Fig. 2.

50 Fig. 5 is another detail vertical sectional view through a part of the feed roll mechanism as taken on the line 5—5 of Fig. 3.

Fig. 6 is a detail horizontal sectional view through another part of the feed roll mechanism as taken on the line 6—6 of Fig. 2.

55 Fig. 7 is a view in elevation showing one side of a fragment of one form of strip that may be advantageously employed in connection with the improved device.

Fig. 8 is a view in elevation showing the other side of the strip fragment illustrated in Fig. 7.

60 Referring now in detail to that embodiment of

the invention, illustrated in the accompanying drawings:

1 indicates, as a whole, the casing of the device and which can be made from any suitable sheet material. Said casing, which is open at the rear, 5 includes a front wall 2, side walls 3—3, a bottom wall 4 and a rounded or semicircular top wall 5. The open rear end of the casing is normally closed by a cover plate 6.

The cover plate 6, which is marginally flanged 10 for stiffness, carries on its inner face at its bottom end, a flange 7 adapted to hook over an upstanding projection 8 on the bottom wall 4. On the inner face of the cover plate near its top end and preferably on the median line thereof, is an 15 inwardly extending flange 9 terminating in an upturned shoulder 10. On the inside of the rounded top wall of the casing is secured a horizontally disposed, U-shaped element 11, providing a stop for the top end of the cover plate. The 20 bottom leg 12 of this element is adapted to engage upon the flange before mentioned with the shoulder 10 engaged with the extremity of said leg as best shown in Fig. 3. The flange 9 which is 25 fairly flexible, includes a lateral extension 13.

In the cover 6 near its top end and to one side of its median line is provided an opening 14 through which a suitable tool (not shown) may be inserted to engage the extension 13 for depressing the same along with the flange 9 so as to disengage the shoulder 10 thereof from behind the member 12 of the U-shaped element 11. This unlocks the cover plate so that the top end thereof may be swung outwardly into a position wherein said cover plate may be lifted upwardly to remove 30 its finger 7 from its hooked engagement with the upstanding projection 8.

35 In the top end of the front wall 2 of the casing and concentric with the rounded or semicircular top wall 5 is a dial opening 15 defined by a 40 bezel 16 for holding a glass 17. In the bottom end of the front wall 2 is a transversely extending slot 18 out through which a predetermined length of a strip may be fed as will soon appear. Between the opening 15 and slot 18 is provided a third or 45 strip portion display opening or window 19, through which a portion of the strip next to be issued is visible. If desired, this opening may be covered by a glass although this is not absolutely essential to the invention.

50 Secured to the inner face of the front wall 2 but arranged a short distance to the rear thereof so as to leave a space 20 is a mechanism supporting plate 21. This plate is formed at its bottom end to provide a pair of rearwardly extending wings 55 22 and 23 respectively, the rear edges of which are adapted to be engaged by the cover plate 6 when the same is in its operative position closing the rear open end of the casing. The plate 21 is further formed near its top end to provide a second 60

pair of rearwardly extending wings 24 and 25 respectively.

In each wing 22, 23 is provided a horizontally disposed slot 26 which opens through its rear edge and arranged above each of said slots and also opening through the rear edge of each wing is a bayonet slot 27. The slots 26 of the wings 22, 23 receive a shaft 28, upon which is mounted a strip 29 in the form of a supply roll 29a. The ends of this shaft project beyond the wings 22, 23 and engaged with each projecting end is the mid portion of a spring or similar means 30, the ends of which are fixed to the rear end portion of the associated wing. In the bayonet slots 27 of the wings 22, 23 is engaged a tension rod 31. The spring arrangement described acts to urge the roll 29a rearwardly of the slots 26 so as to hold the roll in peripheral engagement with the rod 31.

The strip 29 is preferably divided transversely by scored lines 32 into sections 29b or coupon lengths, each bearing on each side thereof suitable indicia. As shown in Fig. 7 one side of said sections may bear successive dates, household hints, recipes, advertising matter and the like, and as shown in Fig. 8, the other side may bear suitable value indicia or other matter. In the margins of the strip, at the associated end of each dividing line 32 is provided a notch or recess 33 that opens through the associated margin of the strip. If desired, said notch may be offset longitudinally to one side or the other of the plane of said line. The purpose of these notches or recesses will soon appear.

In the wings 24—25 before mentioned is journaled a shaft 34. On each end of said shaft just within an associated wing is fixed a feed roll section 35 and 36 respectively, the shaft having a worm gear 37 fixed thereto near the feed roll section 36. The roll section 36 has an outer end extension 38 as best shown in Fig. 5 and mounted on said shaft between a collar 39 and a friction disc 40 is a cam 41. By means of the collar 39 and friction disc 40, the cam 41 under certain conditions can turn relatively to the shaft and under other conditions can turn with said shaft.

The cam 41 includes a finger engageable portion 42 and a contact actuating portion 43. During periods between actual operations of the cam, the end of the cam portion 43 engages a tension roll shaft 44 which is engaged at its ends in bayonet slots 45, one in each wing 24—25. On the tension roll shaft are tension roll sections 46, one associated with each feed roll section.

Supported from and extending between the wings 24—25, is an outer guide 47 for the strip and supported from the rear face of the plate 21 is an inner guide 48 for said strip. These guides in connection with a third guide member 49 provide a strip space or channel 50, up through which the strip 29 extends from the roll 29a, to pass about the roll sections 35 and 36 so as to be guided into and down through the space 20 previously mentioned, toward the slot 18 in the front wall for discharge or issuance out through the same.

On the outer guide 47, to the rear of the roll section 35 is mounted a pair of inner and outer spring contact fingers 51—52 that are suitably insulated from said guide and from each other. The outer or free ends of said fingers are disposed in the plane of the roll extension 38. In the inner guide plate 48 in line with said extension is an opening 53 and this opening is adapted

to register with the recesses or notches 33 in the strip 29 as the same passes up through the guide channel 50 and about the feed roll sections 35 and 36. That margin of the strip having said notches or recesses therein, projects laterally beyond the outer end of the roll section 36 and is there supported only by the inner guide plate 48. In the outer guide plate 47 in line with the opening 53 in the inner guide plate is a second opening 54.

The inner contact finger carries a pin 55 that normally extends through the opening 54 and to engage upon that margin of the strip 29 having the recesses 33 therein. However, when a strip recess 33 registers with the opening 54, the pin 55 passes through said recess and through the opening 53 in the inner guide plate. When the pin 55 is riding on the marginal part of the strip between the recesses 33, then the two contact fingers are electrically engaged. So soon as a recess 33 lines up with the pin 55, the pin passes therethrough and through the opening 53 in the inner guide plate and said inner finger will spring away from the outer one and break engagement therewith so as to open the circuit therethrough.

Projecting rearwardly from the supporting plate 21 and located below those portions of the guides 47, 48 associated with the roll section 36 is a rearwardly extending post 56 made of insulation. This post has secured to one side thereof a pair of top and bottom normally spaced, spring contact fingers 57 and 58 respectively that extend laterally toward the adjacent side wall 3 of the casing. The contact finger 57 is connected by a lead 59 with the contact finger 52 previously mentioned and the contact finger 58 is connected by a lead 60 with one side of a suitable source of current supply.

Suitably supported from the plate 21 and arranged in a position below and in a plane between the roll sections 35—36 is an electric motor 62. This motor which is quite small in size, is a self-starting induction motor and includes a horizontally disposed armature shaft 63 arranged on the vertical median line of the casing and parallel with the side walls thereof. Secured to the rear side of the motor casing is a frame plate 62a in which is journaled a second horizontal shaft 64 arranged at a right angle to and below the armature shaft. Also journaled in said frame plate is a perpendicular shaft 65.

On the rear end of the armature shaft is mounted a worm 66 that meshes with a worm gear 67 on the associated end of the shaft 64. On the other end of the shaft 64 is mounted a worm 68 meshing with and driving a worm gear 69 on the bottom end of the perpendicular shaft 65. The top end of said perpendicular shaft carries a worm 70 which meshes with and drives the worm gear 37 on the feed roll shaft 34 before mentioned.

The field windings of the motor 62 are connected on one side by a lead 71 with the contact 51 and are connected on the other side by a lead 72 with the source of current before mentioned. The pairs of spring contact fingers 51—52 and 57—58 before mentioned form the control for the motor 62 and start and stop the same in timed relation with respect to other parts of the mechanism as will soon appear. When the motor 62 has been started it will operate through the shaft and worm gearing previously mentioned, to drive the feed roll shaft 34.

Supported from the plate 21 and arranged axially in line with the dial opening 15 in the front

wall of the casing is an electric clock indicated as a whole as at 13. This clock has a self-starting, synchronous motor 14 that operates to continuously drive a minute hand shaft 15 and an hour hand arbor 16, the latter of course, being driven two rotations each twenty four hours. In the dial opening 15 is arranged the dial 17 for the clock and on said shaft 15 and arbor 16 are fixed the usual hands for cooperation with the dial.

10 On the hour hand arbor is mounted a gear 18 that drives a larger gear 19 one revolution each twenty four hours. This gear which is fixed on a shaft 20 suitably journaled with respect to the clock motor, carries a lever actuating pin 21 on one side thereof.

Energy for running the clock motor is supplied from a suitable source of means of conductors 22 and 23 respectively. In connection with the supply of energy is means for disconnecting the clock motor therefrom as when the strip 29 runs out or becomes exhausted and such means is as follows:

Suitably arranged in the conductor 23 is a pair of normally closed, or engaged inner and outer spring contact fingers 24 and 25 respectively. 25 These contact fingers which are suitably insulated from each other are mounted upon that part of the guide 47 associated with the feed roll section 35. The inner contact finger 24 carries a pin 26 adapted to extend through suitable openings 27 and 28 in the guides 47 and 48 respectively, just beyond the inner end of the roll section 35.

When the strip 29 is disposed in operative relation in the guide space 50 and is trained about the feed roll sections, the pin 26 will engage and ride on a part of said strip. This will cause said pin to hold the contact fingers 24 and 25 engaged so as to complete the circuit through the conductor 23. When the strip has been exhausted 40 and its end has passed the openings 27—28, the support for the pin 26 is withdrawn so that the pin passes through the opening 28 and causes separation of the contacts 24 and 25. This breaks the circuit for the clock at this point so 45 that the clock will stop.

The clock described is employed to operate means for controlling the "on" and "off" periods for the motor 22 that drives the feed roll shaft 34 and such means is as follows:

50 Along the right hand side wall of the casing as viewed in Fig. 2 is provided a vertically reciprocable bar 89. This bar which is formed for a guided movement on the plate 21 is provided at its top end with a horizontally disposed slot 90. 55 Near its bottom end, said bar carries a pin 91 so arranged that in the upward movement of the bar, said pin will engage the bottom contact finger 58 and cause it to electrically engage the associated contact finger 57. On the rear face of 60 said bar 89 at a point between the slot 90 and pin 91 is provided a spring finger 89a arranged in the plane of the cam 41.

Associated with the twenty four hour gear 19, driven by the clock mechanism as before described, is a lever 92. This lever which is pivoted at a point between its ends as at 93 on the plate 21, includes two arms 94 and 95 respectively. A spring 96 is connected at one end to the plate 21 and is connected at its other end to the lever arm 94 and normally tends to swing the arm in a clockwise direction as viewed in Fig. 2. The other arm 95 carries a pin 97 at its free end and which pin is engaged in the slot 90 of the vertically reciprocable bar 89. The said arm 95 is provided at a point between its ends with a cam

portion 98 and an adjacent recess portion 99 with which the pin 81 on the gear 19 coacts to provide the desired movement to the lever 92 as a whole.

In the issuance of a coupon, section or length 29b of the strip 29, the same is fed out of the slot 18. In the present instance, this feed or issuance occurs only once every twenty four hours and the time element consumed in the same is relatively short. It is, of course, desirable that between actual periods of issuance that said slot 10 be maintained closed so as to prevent some person, out of curiosity or otherwise from inserting some instrument through said slot into the interior of the casing.

In this respect, I have provided a simple and efficient mechanism to open said slot just prior to said issuance and to close the same immediately after such issuance and to hold the same closed until the next issuance.

In carrying out this part of the invention, I 20 provide a slot closing member 100 that has a downwardly inclined portion engaged with the top edge of the slot and includes a lip 101 for closing the bottom of the slot from the inside of the casing. This closing member has upturned ends 25 102, each pivoted as at 103 to an associated wing 22—23 near its front bottom corner. The bottom end of the vertically reciprocable bar 89 before mentioned is offset rearwardly to engage upon that end 102 of the closure member adjacent 30 the wing 23 as best shown in Fig. 3. When the bar 89 is in its lowermost position, this offset bottom end so engages the end 102 of the member 100 as to hold said member in slot closing position. However, in the upward movement of said 35 bar, the member 100 swings in a clockwise direction as viewed in Fig. 3, under gravity action, so that said member and lip operate to open the slot 18.

In operation, during periods between actual 40 issuances, the bar 89 stands in its lowermost position and the contact fingers 57 and 58 are spaced apart. At this time the pin 55 lines up with a recess 33 in the margin of the strip 29 so that the contact fingers 51 and 52 are disengaged, 45 and the motor 22 is deenergized and in its stopped condition. Furthermore, at this time the pin 26, is riding on its part of the strip 29 and the contact fingers 24 and 25 are engaged so that the circuit for the clock motor 14 is closed and the 50 clock is running.

In the rotation of the gear 19 as it is driven, by the motor of the clock, the pin 81 on said gear will engage the cam portion 98 of the arm 95 of the lever 92 and will swing said arm 95 upwardly 55 against the action of the spring 96. By reason of the pin and slot connection 97 and 90 between said arm 95 and the bar 89, an upward movement is imparted to the bar 89. In the initial part of the upward movement of said bar, its spring 60 finger 89a will engage with the portion or tooth 42 of the cam 41 and will swing said cam clockwise as viewed in Fig. 4 until the bar rises to such a height that the finger snaps past said tooth. During this initial part of the movement 65 of said bar, this will turn the cam 41 with respect to the feed shaft and against the holding action of the friction disc 40. In this turning movement of said cam, as it slips with respect to the shaft, the cam portion 43 will engage the end of 70 the inner spring contact finger 51 and will swing the same outwardly to not only withdraw and clear the pin 51 from the recess or notch 33 in the strip 29 but said finger 51 is caused to engage the contact finger 52. This only partially 75

5 closes the circuit for the motor 62 which not being as yet energized remains impasse or inoperative. In this initial part of the upward movement of the bar, the offset bottom end thereof will move away from the portion 102 of the closure member 100 which then swings by gravity into a position providing a free opening for the slot 18.

10 In the final part of the upward movement of the bar 89, the pin 91 thereon engages the lower contact finger 58 and moves the same into engagement with the associated contact finger 57. This completes the closing of the circuit for the motor 62 which now becomes energized. When 15 this motor is running, it will through the shaft 64-65 and associated gearing, drive the feed roll shaft 34. Because of the feed roll sections 25 and 36 thereon and their coaction with the tension roll sections 46, the free end of the strip 29, that terminates at the slot 18 is fed a distance approximating the length of one of its coupons, sections or the like 29b so as to present such a section ready for tearing off and to present another section in line or register with the window opening 19.

20 In the initial part of the drive of the shaft 34 the cam 41 due to its frictional engagement with the shaft, will turn therewith until the front corner part of the cam portion 43 engages the shaft 25 44 for the tension roll sections 46, after which the shaft 34 in the final part of the drive will turn with respect to the cam until an entire section 29b of the strip 29 has been fed out of the slot 18. When the cam 41 is turning with the shaft as mentioned, this will let the spring contact finger 35 51 move toward the guide 47 so that the pin 55 engages and rides on the strip 29. This movement of the spring contact finger, however, is not enough to cause a separation thereof from the associated contact.

40 Just after the time that a complete section of the strip 29 has been fed or issued out of the slot 18, the pin 81 on the gear 79 slips off the cam surface 98 of the lever 92 to enter into the recess 99 of said lever. When this occurs, the arm 45 95 of the lever is left unsupported so that the spring 96 operates to swing said lever in a clockwise direction as viewed in Fig. 2. In this movement of the lever, its arm 95 swings downwardly and through the pin and slot connection 97 and 50 98 causes a downward movement of the bar 89.

45 Just before the time that the lever 92 swings in the clockwise direction as described, a notch or recess 33 in the margin of the strip 29, comes into register with the pin 55 carried by the finger 55 51. This pin then enters the recess 33 and this action causes a separation between the contact fingers 51-52 so that a first and controlling break is provided in the circuit for the motor.

50 In said downward movement of the bar 89 as before mentioned, the pin 91 moves away from the finger 58 and this breaks the motor circuit at a second place.

55 With the issuance of a section of the strip 29 out through the slot 18, a new section is presented to view through the window opening or frame 19 and the issued section may be removed by tearing the same off along the top edge of the slot 18 as a tearing edge.

60 Assume now that the last section of the strip 70 has been fed off the roll and is in a position passing over the feed roll section. As the free edge of said last section passes beyond the pin 86, the same becomes unsupported and this permits the contact finger 84 to move away from the contact

finger 85 and breaks the circuit for the clock motor which stops.

5 It is to be noted that the sets of fingers 51-52 are arranged in the same horizontal plane as the fingers 84-85 just above mentioned. Thus as the free edge of the last section of the strip passes the fingers 84-85 to stop the clock motor, said edge of said section will also pass the fingers 51-52. As this occurs, the pin 55 becomes unsupported so that the finger 51 moves away from the contact 52. This breaks the circuit for the motor 62 which also stops.

10 From the above, it is apparent that when the supply strip is exhausted, this not only stops the clock but it also serves to stop the motor 62. 15 This should only occur once a year and the clock may be again restarted and the device again caused to function only upon the placing of a new supply strip for the following year.

15 The device described, is positive and substantially silent in operation and consists of parts that are strong and rugged so as to require no servicing operation.

20 While I have described the device as issuing a strip length once every 24 hours this is done only 25 in an illustrative sense because with slight modification this time period between issuance may be easily changed.

25 In describing the invention, I have referred in detail to the form, arrangement and construction 30 of the various parts, this is to be considered as descriptive of only one embodiment of the invention, so that I do not wish to be limited thereto, except as may be specifically set forth in the appended claims.

35 I claim as my invention:

1. A device of the kind described embodying therein a casing having a coupon discharge opening, a series of coupons in said casing having the desired indicia thereon, means operative to issue 40 said coupons successively out through said opening at predetermined intervals, means for controlling the intervallic operation of said first mentioned means, and a member for opening and closing said opening and actuated from said controlling means to close said opening between said intervals.

45 2. A device of the kind described embodying therein a casing having a coupon discharge opening, a strip arranged in said casing and having 50 desired indicia on certain portions thereof, means operable to issue said portions successively out through said opening at predetermined intervals, means for controlling the intervallic operation of said first mentioned means, and a member for 55 opening and closing said opening and actuated from said controlling means to close said opening between said intervals.

60 3. A device of the kind described embodying therein a casing having a discharge opening, a strip arranged in said casing and having desired 65 indicia on certain portions thereof, means operable to issue said portions successively out through said opening at predetermined intervals, means for controlling the intervallic operation of said means, and a member for opening and closing said opening and actuated from said controlling means to close said opening between said intervals, and to open said opening just prior to said intervals.

70 4. A device of the kind described embodying therein a casing, a series of coupons in said casing, electrically operated means for issuing said coupons successively at predetermined intervals, and means for starting and stopping said elec- 75

trically operated means to determine said intervals, and including parts actuated by portions of certain of said coupons.

5. A device of the kind described embodying therein a casing, a series of coupons in said casing, electrically operated means for issuing said coupons successively at predetermined intervals, a clock mechanism in said casing, and means actuated partly by said clock mechanism and partly by said coupons for starting and stopping said electrically operated means at the desired intervals.

6. A device of the kind described embodying therein a casing, a strip arranged in said casing and having desired indicia on certain portions thereof, feed roll means in said casing for successively issuing said portions at predetermined intervals, means for actuating feed roll means operating partly through the strip, and means for controlling said actuating means so that said feed roll means will issue said portions at said predetermined intervals.

7. A device of the kind described embodying therein a casing, a strip arranged in said casing and having desired indicia on certain portions thereof, feed roll means in said casing for successively issuing said portions at predetermined intervals, electrically operable means in said casing, means operable by said electrically operable means when energized for actuating said feed roll means operating partly through the strip, and means for controlling the energization of said electrically operable means so that said feed roll means will issue said portions at said predetermined intervals.

8. A device of the kind described embodying therein a casing, a strip arranged in said casing and having desired indicia on certain portions thereof, feed roll means in said casing for successively issuing said portions at predetermined intervals, electrically operable means in said casing, means operable by said electrically operable means when energized for actuating said feed roll means, and clock mechanism in said casing operating in conjunction with parts of the strip for controlling the energization of said electrically operable means so that said feed roll means will issue said portions at said predetermined intervals.

9. A device of the kind described embodying therein a casing having a discharge opening, a strip arranged in said casing and having desired indicia on certain portions thereof, means operable to issue said portions successively out through said discharge opening at predetermined intervals, a member associated with said opening to open and close the same, means for controlling the operation of said first mentioned means, and means actuated in timed relation with said controlling means and operating on said member to open and close said opening in accordance with said intervals.

10. A device of the kind described embodying therein a casing having a discharge opening, a strip arranged in said casing and having desired indicia on certain portions thereof, means for issuing said portions successively out through said opening at predetermined intervals, said means including an electrically operable device as the prime mover, a member associated with said opening for opening and closing the same, a control

mechanism, and means actuated by said control mechanisms for controlling the energization of said electrically operable device and for actuating said member for opening and closing said opening in timed relation with the issuance of 5 said portions of the strip.

11. A device of the kind described embodying therein a casing, a strip arranged in said casing and having desired indicia on certain portions thereof, a feed roll comprising a shaft and roll 10 sections thereon and over which said strip passes, an electrically operable prime mover, speed reducing means between said shaft and prime mover, and means operating partly through the strip for energizing said electrically operable 15 prime mover at predetermined time intervals.

12. A device of the kind described embodying therein a casing, a strip arranged in said casing and having desired indicia on certain portions thereof, a feed roll comprising a shaft and roll 20 sections and over which said strip passes, an electrically operable prime mover, speed reducing means between said shaft and prime mover, a circuit for said prime mover, and mechanism also in said casing and operating partly through the strip 25 for controlling said circuit at predetermined time intervals.

13. A device of the kind described embodying therein a casing, a strip arranged in said casing and having desired indicia on certain portions 30 thereof, a feed roll comprising a shaft and roll sections and over which said strip passes, an electrically operable prime mover, speed reducing means between said shaft and prime mover, a circuit for said prime mover, clock mechanism 35 in said casing for controlling said circuit at predetermined intervals, and means for stopping said clock mechanism when the tail end of said strip passes over said feed roll.

14. A device of the kind described embodying 40 therein a casing, a strip arranged in said casing, electrically operable means for issuing successive portions of said strip at predetermined intervals, a circuit for said means, sets of contact members arranged in said circuit for controlling the open- 45 ing and closing of the same, means operating in timed relation with said intervals for actuating said sets of contact members to close said circuit, one contact of one of said sets when in circuit closing position engaging said strip, and means 50 associated with predetermined portions of said strip and operating when it comes into line with said contact of said one of said sets of contact members to open said circuit for said electrically operable means. 55

15. A device of the kind described embodying therein a casing, a strip arranged in said casing, electrically operable means for issuing successive portions of said strip at predetermined intervals, a circuit for said means, sets of contact members 60 arranged in said circuit for controlling the opening and closing of the same, clock mechanism for determining said intervals, and means operated by said clock mechanism for actuating said sets of contact members to close said circuit, one of 65 said sets of contacts being actuated by the strip itself to open said circuit at one point and the other of said sets of contacts being actuated by said clock mechanism actuated means to open said circuit at another point. 70

EDWARD H. PHILIPPI.
